UNITED STATES PATENT OFFICE.

HANS SCHEFTLEIN, OF CHRISTIANIA, NORWAY, ASSIGNOR TO NORSK HYDRO-ELEKTRISK KVÆLSTOFAKTIESELSKAB, OF CHRISTIANIA, NORWAY.

BOILER FOR THE PRODUCTION OF STEAM OR FOR THE EVAPORATION OF SOLUTIONS.

1,180,545.

Specification of Letters Patent.

Patented Apr. 25, 1916.

Application filed November 1, 1913. Serial No. 798,714.

To all whom it may concern:

Be it known that I, HANS SCHEFTLEIN, a subject of the Emperor of Germany, residing at Christiania, Norway, have invented 5 certain new and useful Improvements in Boilers for the Production of Steam or for the Evaporation of Solutions; and I do hereby declare the following to be a full, clear, and exact description of the invention, such as 10 will enable others skilled in the art to which it appertains to make and use the same, reference being had to the accompanying drawings, and to letters or figures of reference marked thereon, which form a part of this 15 specification.

In the production of nitrogen products by the conibustion of the nitrogen of the atmosphere in an electric high voltage flame a comparatively small portion only of the 20 heat developed by the electric energy is utilized for the oxidation process. Attempts have therefore been made to utilize by various means the heat of the gases issuing from the nitrogen furnace for other technical purposes, for instance the gases have been conducted through boiler plants. The efficiency 25 however of these systems for utilizing the heat, has not been very great. On one hand the large cost of installation and the large 30 space required relatively to the heat obtained, and on the other hand the large losses of heat caused by the passage of the gases through pipes or channels, will act to reduce the productiveness of the plants. 35 Said drawbacks will all be avoided, when according to the present invention, the nitrogen furnace is made integral with the boiler plant which is possible when choosing suitable types of nitrogen furnace as well as of 40 boiler plant.

According to the present invention a nitrogen furnace of the tube-furnace type (*i. e.* the kind of high voltage furnace in which the flame is drawn out mainly by the action 45 of a powerful current of air) is mounted in a boiler of a construction suitable for the purpose so that the nitrogen furnace will replace the fire-box. Thus all the heat developed in the nitrogen furnace, and not utilized for the oxidation of the nitrogen, will in this manner be supplied to the boiler without loss of heat.

According to the invention a boiler of a combined flue and smoke tube system is used

for this purpose, the vertical form of such a 55 boiler being particularly suitable.

The invention comprises not only the combination of nitrogen furnace and boiler referred to, but also the utilization of the boiler plant thus obtained for other purposes, thus in the first place as evaporators 60 for the solution (nitrate or nitrite solution, etc.) obtained in the production of the nitrogen products, which will be hereafter more particularly explained.

In the accompanying drawing are shown two forms of boiler plants in accordance with the present invention.

Figures 1 and 2 are a vertical section and a cross-section respectively of a boiler-construction in which the nitrogen furnaces have been placed in position from below, Figs. 3 and 4 being corresponding sections of a boiler construction in which the nitrogen furnaces have been introduced from 75 above.

In the former form the boiler has a flame tube A and smoke tubes B mounted between the end walls C and D of the boiler. Beneath the tube wall C is formed a chamber F insulated by chamotte E or the like and connecting the flue A to the smoke tubes B. At the top the gases pass from the smoke tube into a chamber G whence they are conducted on to cooling apparatus, etc. Said 80 chamber is separated from the flue A by a chamber made of chamotte and which is carried so far downward in an enlarged portion of the flue that its lower end will be a sufficient distance below the steam chamber of 85 90 the boiler.

Mounted in the flue are three nitrogen furnaces K of a well-known type (in the longitudinal sectional view only one furnace has been shown). The air enters at L and 95 passes through the nitrogen furnaces in the direction of the arrows.

M is the water-cooled portion of the furnace. This cooling, which is used to avoid too great dissociation, however, may be effected by means of a current of air according to known methods. The oxidation gases are discharged into the chamber H. On account of the high temperature of the gases said chamber will act as quite a powerful 100 superheater. In the flue A, through 105 which the gases pass in a downward direction, the same will give off so much of their

heat as not to have any destructive effect, in the chamber F, on the connection of the smoke tubes with the boiler wall. At this point the gases will also have a temperature rendering them fit for use in calorifères for heating air to be used in the concentration of nitric acid, for which reason an outlet N is suitably provided for this purpose at that point.

One or more furnaces may be provided in each flame flue the latter arrangement being of a certain advantage owing to the fact that the peculiar pumping motion of the flame and the gases which takes place in the nitrogen furnaces, will thereby be neutralized.

In the furnace according to Figs. 3 and 4, in which the reference characters correspond to those in Figs. 1 and 2, three flame flues A (each having one nitrogen furnace K introduced in it from above) and four groups of smoke tubes B, have been provided and arranged as shown in Fig. 4. The smoke tubes are not mounted in the bottom plate C of the boiler, but in plates R forming the end walls of shorter flues S, which communicate through the chamber F with the flues A and in which the gases are allowed to cool before reaching the smoke tubes. Each flue A has an extension tube T into which the furnace is introduced from above.

The arrangement of one furnace in each flue has the advantage that closing devices, of a simple construction may be provided so that each furnace may be separately dismounted without interfering with the operation of the furnaces in the remaining flame flues.

The furnace is provided with an air pre-heating device which consists of a plurality of concentric cylinders U arranged to form communicating annular passages through which air, supplied from the inlet L, passes, in the directions indicated by the arrows in Fig. 3, and is preheated before it reaches the arc in the central flue k of the furnace through which said air passes downward into the flame flue A. A cooling chamber M surrounds the lower portion of the central flue and is supplied with a cooling medium which is circulated through pipes m.

A sufficient distance below the top of the steam chamber of the boiler, the flame flue A is contracted and the outer cylinder of the air preheater is correspondingly enlarged so as to form a restricted annular passage V. This passage serves to prevent the hot gases in the flue A from freely entering the upper part of the annular space J, formed between the tube T and the air preheater, as it is essential that said annular space shall not be too highly heated where the tube T is not surrounded by water.

As is already mentioned, the boiler systems herein referred to may advantageously be used for evaporating a solution obtained

in absorption processes conducted with liquids. For this purpose the boilers are used simultaneously for storing heat for heating and for the first step of the evaporation, the amounts of heat contained in the 70 gases after the same have passed the boilers, are afterward used for the final concentration by means of known evaporating apparatus which accordingly are heated directly with the nitrous gases obtained, instead of 75 with steam or direct firing.

By such an arrangement considerable advantages are obtained: The boilers, which in this construction will operate under atmospheric pressure or vacuum, require much 80 less strength of construction, all the steam pipes leading to the usual evaporating apparatus will be done away with, and the operation will be without all the dangers or difficulties incident to the operation with 85 high-pressure steam.

Besides great economy of the prime cost and of space, a far better efficiency of the plant is obtained, eliminating all the losses which arise in the absorption devices now 90 in use owing to the fact that the heat of the gases is first utilized for the production of steam.

If it is desirable to drive part of the auxiliary machinery (such as compressors, pumps, 95 or the like) by means of steam engines, part of the boilers may be constructed to produce the necessary high pressure-steam. The remaining boilers being constructed for use in evaporating the solution. 100

In several of the processes now in use for extracting the nitrogen of the atmosphere the nitrous gases obtained are absorbed with water, a comparatively weak acid (up to 105 65%) is then obtained, said acid being advantageously concentrated to an acid of ordinary commercial strength. If in the usual manner sulfuric acid be used for this so-called high concentration, the same will have to be reconcentrated, hot air of temperatures up to about 500° C. and superheated steam of temperatures up to above 300° C. being advantageously used for said reconcentration. 110

I claim:

1. The combination of a steam boiler having a flame flue therein, a steam chamber surrounding the flue, a plurality of fire tubes extending through said chamber and communicating with the flue through one 120 end thereof, and a high voltage arc furnace arranged to discharge its gases into the flue at a distance from said end, whereby the temperature of the gases is lowered before entering the tubes. 125

2. The combination of a steam boiler having a flame flue therein, a steam chamber surrounding the flue, a plurality of fire tubes extending through said chamber and communicating with the flue through one 130

- end thereof, a high voltage arc furnace arranged to discharge its gases into the flue at a distance from said end, and a cooling device at the discharge end of the furnace. 5
3. The combination of a steam boiler having a flame flue therein, a steam chamber surrounding the flue, a plurality of fire tubes extending through said chamber, a high voltage arc furnace extending into the flue through the top of the boiler chamber, and short flues at the bottom of the latter communicating with the flame flue and fire tubes. 10
4. The combination of a steam boiler having a flame flue therein, a steam chamber surrounding the flue, a plurality of fire tubes extending through said chamber and communicating with the flue through one end thereof, a high voltage arc furnace arranged to discharge its gases into the flue at a distance from said end, and means situated between the flue and pipes for drawing off gases reduced in temperature. 15
5. The combination of a steam boiler having a flame flue therein, a high voltage arc furnace extending into the flue through the top thereof, a steam chamber surrounding the flue, short flues extending upward into the steam chamber parallel to the flame flue and communicating with the latter through a chamber situated below the steam chamber, fire tubes communicating with the short flues and extending through the steam chamber, and means in the furnace for pre-heating air supplied thereto before it reaches the arc. 20
6. The combination of a steam boiler having a flame flue therein, a high voltage arc furnace extending into the flue through the top thereof, a steam chamber surrounding the flue, short flues extending upward into the steam chamber parallel to the flame flue and communicating with the latter through a chamber situated below the steam chamber, fire tubes communicating with the short flues and extending through the steam chamber, and means in the furnace for pre-heating air supplied thereto before it reaches the arc. 25
- 40
- 45
- flues and extending through the steam chamber, means in the furnace for pre-heating air supplied thereto before it reaches the arc, and means to cool the gases issuing from the furnace. 50
7. The combination of a steam boiler having a flame flue therein, a high voltage arc furnace extending into the flue through the top thereof, a steam chamber surrounding the flue, short flues extending upward into the steam chamber parallel to the flame flue and communicating with the latter through a chamber situated below the steam chamber, fire tubes communicating with the short flues and extending through the steam chamber, means in the furnace for pre-heating air supplied thereto before it reaches the arc, means to cool the gases issuing from the furnace, and means in the flame flue to retard an upward movement of the gases therein. 55
8. The combination of a steam boiler having a flame flue therein, a high voltage arc furnace extending into the flue through the top thereof, a steam chamber surrounding the flue, short flues extending upward into the steam chamber parallel to the flame flue and communicating with the latter through a chamber situated below the steam chamber, fire tubes communicating with the short flues and extending through the steam chamber, means in the furnace for pre-heating air supplied thereto before it reaches the arc, means to cool the gases issuing from the furnace, and means in the flame flue to retard an upward movement of the gases therein. 60
